DESIGN FOR A CAKE BOX COVER

Martha H. Connor, Baltimore, Md., assignor to Owens-Illinois Can Company, Wilmington, Del.,
a corporation of Delaware

Application September 30, 1936, Serial No. 65,091

Term of patent 7 years

To all whom it may concern:

Be it known that I, Martha H. Connor, a citizen of the United States and residing at Baltimore, in the State of Maryland, have invented a new, original, and ornamental Design for a Cake Box Cover, of which the following is a specification, reference being had to the accompanying drawing forming a part thereof.

In the drawing:

Fig. 1 is a top plan view of a cake box cover showing my new design, the stippled areas representing a color different from the remaining areas; and

Fig. 2 is a side elevational view thereof.

I claim:

The ornamental design for a cake box cover substantially as shown and described.

MARTHA H. CONNOR.
